UNITED STATES PATENT OFFICE.

BION B. WHITNEY, OF STANDISH, MAINE, ASSIGNEE OF ONE-HALF TO LYNWOOD B. WHITNEY, OF STANDISH, MAINE.

WRENCH.

1,119,655.

Specification of Letters Patent.

Patented Dec. 1, 1914.

Application filed June 10, 1914. Serial No. 844,191.

To all whom it may concern:

Be it known that I, BION B. WHITNEY, a citizen of the United States, residing at Standish, in the county of Cumberland and State of Maine, have invented certain new and useful Improvements in Wrenches, of which the following is a specification.

My invention relates to improvements in wrenches, particularly well adapted for use in connection with pipes, rods or the like, while not necessarily restricted to such use.

The invention aims to provide a wrench of the above mentioned character, which is exceedingly simple in construction, and inexpensive to manufacture; to provide a wrench so constructed that the pressure upon the handle or lever thereof is directly transmitted to the pivoted jaw; and to provide a wrench having means for automatically 20 swinging the pivoted jaw away from the work, upon the removal of pressure from the lever, whereby the jaw will not stick to the work.

In the accompanying drawings forming a part of this specification and in which like numerals are employed to designate like parts throughout the same, Figure 1 is a side elevation of a wrench embodying my invention, Fig. 2 is an enlarged fragmentary side 30 elevation of the same, parts being shown in section for the purpose of illustration, and, Fig. 3 is a transverse sectional view taken on line 3—3 of Fig. 2.

In the drawings, wherein for the purpose of illustration is shown a preferred embodiment of my invention, the numeral 5 designates the housing or frame, within which is mounted to reciprocate a shank 6 carried by a relatively stationary longitudinally adjustable laterally extending jaw 7. Upon its inner face the jaw 7 is provided with teeth 8, as shown. The shank 6 and the opening of the housing 5 receiving the same are preferably formed rectangular in cross-section, as clearly illustrated in Fig. 3. The housing 5 is provided near its inner end with a transverse opening 9, receiving a milled adjusting nut 10, engaging a screw-threaded extension 11 rigidly secured to the inner end of the shank 6, as shown.

Extending in the same direction with the relatively stationary jaw 7 are ears or extensions 12, projecting laterally beyond the shank 6 for a substantial distance, the housing 5 being provided between these ears with

a longitudinal opening 13, as shown. Arranged between the forward ends of the ears 12 is a swinging jaw 14, pivoted to the ears as shown at 15. This jaw is provided upon its inner face with teeth 16. The jaw 14 has a shank 17 rigidly secured thereto, which carries a suitably stiff leaf spring 18, rigidly secured thereto. This shank 17 and the leaf spring 18 extend longitudinally of and approximately parallel with the shank 6, as shown. The function of this leaf spring is to automatically swing the pivoted jaw 14 away from the relatively stationary jaw, to release the work, when pressure is taken off of the operating handle, as will be more fully explained.

The numeral 19 designates an operating lever or handle carrying at its inner end a hand grip 20. At its outer end the operating lever is provided with a lateral extension or crank 21, the free end of which is adapted to directly engage the outer portion of the pivoted jaw 14 to swing the same toward the relatively stationary shank. The operating lever 19 is arranged between the spaced ears 12 and pivoted thereto, at the inner end of the lateral extension or crank 21, as shown at 22. The leaf spring 18 is confined between the shank 6 and the operating lever 19, and is so tensioned that it exerts pressure upon the operating lever, whereby the same tends to swing the pivoted jaw 14 away from the jaw 7, when the operating lever 19 has returned to its position parallel with the shank 6, as shown in Fig. 2.

In use, the nut 10 is operated whereby the jaws 7 and 14 are moved apart sufficiently to receive the work, such as a pipe, rod or the like. The operator then takes hold of the hand grip 20, and turns the pipe clockwise as is customary. During this operation, the operating lever 19 can partake of perceptible swinging movement with respect to the shank 6, the same turning upon the pivot 22, whereby crank 21 engages the outer end of the swinging jaw 14, swinging the same inwardly with respect to the stationary jaw 7 to increase the clamping engagement with the work. When the operating lever 19 is swung in an opposite direction to release the work, spring 18 quickly moves the jaw 14 away from jaw 7 whereby this jaw disengages the work, allowing the wrench to be swung in an opposite direction or to be removed from the pipe, if desired.

It is to be understood that the form of my invention herewith shown and described is to be taken as a preferred example of the same, and that various changes in the shape, size, and arrangement of parts may be resorted to without departing from the spirit of the invention or the scope of the subjoined claim.

Having thus described my invention, I 10 claim:—

A wrench comprising a housing having laterally extending spaced ears, a shank longitudinally adjustably mounted within the housing and carrying a relatively stationary jaw, a co-acting jaw arranged opposite the relatively stationary jaw and pivotally connected with the housing and carrying at its inner end an extension extending longitudinally of and approximately parallel with the shank, a lever arranged upon the

same side of the shank with the pivoted jaw and pivotally connected with the spaced ears and provided at its free ends with a laterally off-set portion adapted for direct engagement with the outer end of the pivoted 25 jaw and affording a space between the same and the shank for the longitudinally extending extension of the pivoted jaw, and a relatively flat leaf spring attached to the outer end of the longitudinal extension on said 30 pivoted jaw and extending approximately parallel with the shank and arranged between the same and the pivoted lever, substantially as described.

In testimony whereof I affix my signature 35 in presence of two witnesses.

BION B. WHITNEY.
